UNITED STATES PATENT OFFICE

PHILIP B. SHAILER AND HARRY P. TROENDLY, OF CHICAGO, ILLINOIS, ASSIGNORS TO
THE WM. D. GIBSON COMPANY, OF CHICAGO, ILLINOIS, A CORPORATION OF ILLINOIS

MIXING DEVICE

Application filed May 11, 1931. Serial No. 536,338.

This invention relates to a mixing device and has special reference to a drink mixer which is hand operated to provide a vertically reciprocal motion to a dasher for aerating and violently agitating a solution in an enclosed receptacle.

More particularly, this invention relates to a mixing device comprising an open top receptacle preferably of glass having a cover 10 for enclosing the same, the cover providing a bearing for a dasher shaft extending therethrough for vertically reciprocal motion and the shaft supporting a perforated conical dasher within the receptacle.

The above elements broadly considered are common to a particular class of mixing devices now on the market, which latter, however, are objectionable in that some of the liquid is displaced from the receptacle 15 through the opening for the dasher shaft and through the seal between the cover and the receptacle. The liquid thus dissipated flows over the outer sides of the receptacle to soil the hands of the operator and to leave 20 a ring or other unsightly appearance on the table or other support therefor. Tremendous sales resistance is caused by these objectionable features in an otherwise very useful household utensil.

It is the contemplation of the present invention to eliminate the above noted objectionable features by so constructing the bushing as to wipe the shaft substantially free 25 from liquid on its upward stroke. Also, an efficient seal is provided by means of slightly tapering the peripheral cover engaging edge 30 of the receptacle.

This invention further contemplates the improvement of the conical dasher by providing 35 a series of radial slots extending a substantial distance inwardly from the outer periphery of the cone. A thorough agitation of the liquid is caused by the slots in the vertical reciprocation of the dasher shaft and the solution is aerated to a highly satisfactory degree by the crossing of the circulatory paths of the agitated solution and by the provision of an air trap above the slots within 45 the cone which confines the air contiguous to the surface of the solution and forces the

same to the bottom of the receptacle before releasing.

It is further contemplated to provide a dasher in which the correct relation of the area of the slots with the cross-sectional area 55 of the receptacle is obtained whereby the operator may force the solution through the slots at a very high and efficient velocity.

One of the objects of this invention is to provide a mixing device of the type hereinbefore referred to which is inexpensive to manufacture, is efficient in operation and is durable.

Another object of this invention is to provide a device of the character noted above in 65 which the solution is effectively sealed within the container.

A further object of this invention is to provide a mixing device of the type above pointed out in which the dasher thereof will effectively agitate and aerate the solution.

Other objects and advantages will hereinafter be more fully pointed out and for a more complete understanding of the characteristic features of this invention reference 75 may now be had to the following description when taken together with the accompanying drawing, in which latter:

Figure 1 is a central sectional view of the device of this invention;

Fig. 2 is a fragmentary enlarged view of a portion of the cap and the receptacle showing the engaging or sealing relation therebetween;

Fig. 3 is a central sectional view of the 85 bushing for the agitating shaft; and

Fig. 4 is a fragmentary sectional view of a modified form of bearing for the agitating shaft.

Referring now more particularly to the 90 drawing, the device of this invention preferably comprises an open top tapered receptacle 10 preferably formed of glass having a sheet metal stamped cover 11 for enclosing the open top. Although a glass receptacle 95 is preferable it will be understood that a receptacle of any suitable material may be employed in lieu thereof. The cover is preferably provided with a bushing 12 through which a dasher shaft 13 extends and which 100

shaft is vertically reciprocated therethrough. The upper end of the dasher shaft is preferably bent to form a handle 14, the lower end thereof passing through a hole 15 in the upper end of dasher 16. A securing relation between the dasher and dasher shaft is provided as by means of spot welding the lower end of the shaft to the material adjacent a hole in a raised portion at the apex of the preferably cone-shaped dasher 16 through which hole the shaft extends.

The dasher 16 is preferably made in the form of a substantially conical shell having an apron extending angularly from the peripheral base thereof and is provided with a series of radial slots 18 extending preferably from the outer periphery thereof a substantial distance inwardly therefrom. It is also to be noted that the slots need not be extended to the peripheral edge but may be wholly internal of the shell with effective results. In order to operate efficiently, the slots 18 should have a fixed area with respect to the total cross-sectional area of the receptacle so as to force the solution through the slots at a high velocity during the reciprocation of the dasher at a normal speed of operation. This ratio has been determined by relating the vertically projected area to an average cross-sectional area since the side wall of the receptacle is shown as being tapered. It is, of course, to be understood that the side wall of the receptacle may be vertical or shaped in any manner desired. By "vertically projected area" is meant the effective area available for vertically rising liquid in the receptacle which is equivalent to the sum of the shadows which the slots cast on a horizontal plane if beams of light came from infinite distances vertically above the slot.

The area of the slots which have been found to be more particularly desirable represent a vertically projected area of approximately 41 1/4% of the total average area of the receptacle. From a practical standpoint, the area of the slots should be maintained between 1 1/2% and 13% of the average area of the glass for effective results. Inasmuch as the upper end of the conical shell is enclosed and the slots 18 do not extend the full length of the side walls, an air trap 19 is provided, the action of which will be hereinafter more fully explained.

Mixing devices of the type herein described have been quite objectionable in that the solution to be mixed therein may be readily displaced from the receptacle through the opening at the bearing through which the dasher shaft 13 is reciprocated. The present invention contemplates the provision of a member preferably extending inwardly toward the receptacle which we may call a reentrant member which will act as a bearing for guiding the dasher shaft 13, the bushing being in the shape of an inverted substantially coni-

cal shell having a very small shaft engaging portion 20 to reduce to a minimum friction between the shaft and the bushing and to provide by reason of the tapered wall 21 on the outside of the shell a sharp edge 22 to 70 the periphery of the shaft 13 for preventing creeping of the solution upwardly and outwardly along the shaft outside of the receptacle. As the shaft 13 is reciprocated the solution clinging thereto is wiped off by the sharp edge 22 on the upward movement of the shaft and when a sufficient amount forms at the lower end of the shell it is drained back into the receptacle. As a precautionary measure, by reason of the bushing being 80 a shell of a substantially conical shape, a receiving cup 23 is provided between the inner wall of the shell and the vertical shaft to collect any moisture that may become displaced from the receptacle. In the event that 85 a small amount of solution may become displaced from the receptacle into the receiving cup, that amount would be carried back into the shell by the suction created by the dasher on the downward movement of the shaft 13 90 and consequently the solution would not be permitted to escape from the cup 23 over on to the cover 11.

In order to seal completely the solution to be mixed within the receptacle, the upper end 95 of the receptacle 10 is provided with a circular recess 24 preferably of substantially the same depth as the thickness of the cover 11 engaging therewith. The cover 11 is preferably of an inverted cup-shape having a flange 100 25 of substantially the same height as the height of the recess 24 in which it engages. The flange, it will be noted, is merely a continuation at a slight angle of the main body portion of the cover and contains no beading 105 or similar portion for the purpose of rigidity, since it is desired that the cover be of the utmost flexibility. For want of a better term and to eliminate the use of negative limitations, the cup-shaped cover will hereinafter be referred to as having substantially straight side walls and in the use of this terminology the use of expressions such as not having a bead or other reinforcing portion will be avoided. The inner recessed wall of the receptacle converges inwardly from a point substantially midway of the height thereof to a radial portion forming a shoulder with the inside tapered wall of the receptacle to receive in sealed engagement therewith the outer wall of the flange 25 of the cover 11 which effectively prevents a dissipation of the solution outside of the receptacle at this point. It has been found that the wall of this circular recess at the top of the receptacle 120 10 may taper about one degree from the vertical to engage the vertically extending flange 25, although the latter has been found to give effective results by tapering in a direction opposite to that of the wall of the receptacle 125 110 115 125 130

about one degree. It is, of course, to be understood that these figures are merely for the purpose of providing an operative structure and may be varied to produce effective results. For example, either one or both engaging walls may be tapered, although the form illustrated has been found to be more desirable from a commercial standpoint. It is to be noted that in molding the glass receptacle there are certain limits as to the accuracy obtained and the contour may be slightly oval shaped or the diameter may vary to some degree. The construction of the present invention accommodates these variances by reason partly of the resiliency of the cap and partly by the tapered engaging edge or edges. It is also particularly pointed out that the seal between the cap and receptacle is effected within the container as differentiated from a seal as usually provided in articles of this character outside of the receptacle.

In the operation of the device, the dasher shaft is vigorously reciprocated whereby the solution in the receptacle is agitated and aerated and thereby caused to have a frothy appearance due to the tiny voids created in the solution. The appearance of the solution is particularly inviting to the eye and the frothy aerated mixture has been found to be more palatable. On the downward stroke of the dasher, air is trapped in the chamber 19 thereof and is carried down to the bottom of the receptacle where it is released therein on the upward stroke of the dasher. Air contiguous to the surface of the liquid, of course, is forced into the liquid at the top of the receptacle in the same manner and a substantial supply of air is thereby passed into the solution. Also, the downward stroke of the dasher sets up a circulatory movement in one direction which is broken up by a movement of the dasher in the opposite direction setting up a second circulatory movement of the liquid. The mixing of the solution and the aerating thereof is augmented by the series of radial slots on the dasher through which the liquid must pass at a very high velocity due particularly to the relations of the areas of the slots and the cross-sectional area of the receptacle. The various circulatory movements of the liquid together with the violent agitation thereof and the trapping of the air by the dasher further provides effective mixing and aerating of the solution.

The receptacle 10 has been described as being preferably formed of glass for the reason that it can be easily kept clean and is not liable to rust or become oxidized or have the solution cling thereto as in a metallic or other receptacle. Also, being transparent the receptacle will allow the contents thereof to be seen while the dasher is being reciprocated. The other elements of the construc-

tion may be plated with a non-corrosive substance.

Referring now more particularly to Fig. 4 of the drawings, a sheet metal stamped cover shown therein is of the same form in all respects to that previously recited with the exception that instead of a separate reentrant member the material adjacent the opening in the cover through which the shaft extends is formed into a reentrant substantially conical shell 26 having a small bearing portion 27 engaging the dasher shaft. A sharp edge 28 is preferably provided at the small end of the conical shell for wiping or preventing creeping of the solution from the shaft out of the receptacle as in the previous modification. The large end of the shell provides a cup portion 29 on the inner side thereof which may receive any liquid displaced from the container, such liquid being carried back into the shell by the suction created by the dasher on the downward movement of the dasher shaft.

While but two embodiments of this invention are herein shown and described, it is to be understood that various modifications thereof may be apparent to those skilled in the art without departing from the spirit and scope of this invention and, therefore, the same are only to be limited by the scope of the prior art and the appended claims.

We claim:

1. In a device of the class described, a rigid receptacle having an open top, an inverted relatively thin sheet metal cup-shaped cover having substantially straight side walls for providing a desired flexibility in said cover, an agitator shaft extending through said cover, and a dasher movable by said shaft to agitate a solution in said receptacle, the inner wall of said receptacle adjacent said open top receiving in sealed engagement therewith the peripheral wall of said cover to prevent a displacement of said solution outside of said receptacle, the walls of said receptacle converging in one direction and said cover converging in an opposite direction.

2. In a device of the class described, a rigid receptacle having an open top, an inverted relatively thin sheet metal cup-shaped cover having substantially straight side walls for providing a desired flexibility in said cover, an agitator shaft extending through said cover, and a dasher movable by said shaft to agitate a solution in said receptacle, the inner wall of said receptacle adjacent said open top converging inwardly to an arcuate portion forming a shoulder with the inside wall of said receptacle to receive in sealed engagement therewith the peripheral wall of said cover to prevent a displacement of said solution outside of said receptacle.

3. In a device of the class described, a

rigid receptacle having an open top, an inverted relatively thin sheet metal cup-shaped cover having substantially straight side walls for providing a desired flexibility in said cover, said cover having a reentrant substantially conical shell for providing a bearing, an agitator shaft extending through said bearing of said cover, and a dasher movable by said shaft to agitate a solution in said receptacle, the inner wall of said receptacle adjacent said open top receiving in sealed engagement therewith the peripheral wall of said cover to prevent a displacement of said solution outside of said receptacle, the walls of said receptacle converging in one direction and said cover converging in an opposite direction.

4. In a device of the class described, a rigid receptacle having an open top, an inverted relatively thin sheet metal cup-shaped cover having substantially straight side walls for providing a desired flexibility in said cover, an agitator shaft extending through said cover, and a dasher movable by said shaft to agitate a solution in said receptacle, the inner wall of said receptacle adjacent said open top converging inwardly to receive in sealed engagement therewith an outwardly converging wall of said cover to prevent a displacement of said solution outside of said receptacle.

5. A dasher for reciprocal movement in a receptacle comprising a substantially conical shell having an apron extending angularly from the peripheral base thereof, said shell having a plurality of radial slots extending from the outer edge thereof substantially inwardly therefrom and being enclosed at the apex thereof to provide an air trap.

40 In witness whereof, we have hereunto subscribed our names.

PHILIP B. SHAILER.
HARRY P. TROENDLY.
